(57) CLAIM

The ornamental design for a disposable shower mat, as shown and described.

DESCRIPTION

FIG. 1 is a perspective view of a disposable shower mat showing our new design;

FIG. 2 is a top plan view thereof;

FIG. 3 is a side elevational view thereof, all other side elevational views being identical thereto; and,

FIG. 4 is a reduced scale perspective view showing the disposable shower mat in condition of use. The broken line environmental structure is for illustrative purposes only and forms no part of the claimed design.
